Primary Examiner — Angela J Lee(74) *Attorney, Agent, or Firm* — Quarles & Brady LLP; James J. Aquilina(57) **CLAIM**

The ornamental design for an electronic device support, as shown and described.

DESCRIPTION

FIG. 1 is a top, left, and front perspective view of an electronic device support showing our new design;

FIG. 2 is a bottom, left, and front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the electronic device support that form no part of the claimed design.

1 Claim, 8 Drawing Sheets(56)
